PAVEMENT SLAB CONNECTING MEANS

Franklin W. Abel, Franklin, Ind.

Application May 16, 1945, Serial No. 593,997

8 Claims. (Cl. 94—8)

1

This invention relates to pavements and particularly to that type of pavement formed from individual, precast slabs one interconnected with another to secure what I term controlled rigidity throughout the entire pavement and particularly in respect to the interconnecting means between adjacent slabs. An important advantage of the invention is that the slabs may be formed at a central plant or station and then taken to the site of the roadway and placed in position upon a sub-base, one slab after another, and those slabs interconnected to provide a continuous paved roadway with means holding the slabs at a common level or with their sides in the grade required, all in such a manner that the slabs cannot work apart one from the other or one slab raise or lower in respect to the other.

Another advantage of the invention is found in the fact that where the occasion arises to open up the roadway to make sewer connections, repairs, gas or water main connections, and the like, no pavement has to be chopped through and then have a hole refilled either leaving a depression or a raised portion as customarily occurs. Instead, all that is necessary is to disconnect one slab from its adjacent slabs, and then lift that slab vertically upwardly and shift it horizontally from over the location where the excavation has to be made. Then following the completion of the work and the refilling of the excavation, the slab may be shifted back over the original setting and lowered between the other slabs or alongside thereof as the case may be and then reconnected so that the smooth surface of the roadway is again had.

These and other important objects and advantages of the invention will become apparent to those informed in road paving in the following description of one particular form of the invention as illustrated in the accompanying drawings, in which

Fig. 1 is a view in top plan of a fragmentary portion of a roadway embodying my invention;

Fig. 2, a vertical longitudinal section on the line 2—2 in Fig. 1;

Fig. 3, a transverse vertical section on the line 3—3 in Fig. 1; and

Fig. 4, a top plan view on an enlarged scale of one of the slab interconnecting means within a well and with the cover removed.

Like characters of reference indicate like parts throughout the several views in the drawings.

Reference is made to my copending application for United States Letters Patent, Serial Number 556,363, of which this application is a continuation in part.

As indicated in Fig. 1, the roadway is built up by laying one after another slabs 10 of any desired area, depending upon the nature of the roadway, and the ability to lift and transport

them. Each slab 10 is made to have sides and edges at right angles to each other so that they may be laid one after another to have sides and ends brought respectively adjacent each other, either in a staggered relation or as indicated in Fig. 1, in aligned, cornering relation. It is desired that the slabs be spaced apart a sufficient distance, as indicated in Fig. 1, to permit insertion therebetween of a waterproof sealing strip 11, serving also as a compressible joint under expansion of the slabs.

Each slab 10 is provided with one or more wells 12 along predetermined sides and ends, the well being herein shown as a rectangular recess entering from the edge and being cut entirely vertically through the slab. In the end of the well 12, within a recess 13 is mounted the base 14 of a T iron to have a tongue 15 extend horizontally therefrom. The base 12 is anchored to the slab 10 by means of two cap screws 16 and 17 passing through the base 14 on each side of the tongue 15 and screw-threadedly engaging within a frustoconical lead sleeve 18 in each instance that has been positioned within the slab at the time it was formed, this particular construction forming the subject matter of my United States Letters Patent No. 2,396,803, issued March 19, 1946. In any event, the recess 13 is sufficiently deep as to receive entirely therewithin the heads of the cap screws 16 and 17.

Now in the next adjacent slab 10, Fig. 2, being the slab shown on the left hand side, there is likewise affixed thereto the base 19 within the recess 20 of the slab by the two cap screws 21 and 22 screw-threadedly engaging in the lead, frustoconical sleeves 23 and 24 embedded within the slab. From this base 19 extends the tongue 25 at the same level as that of the tongue 15. When the two adjacent slabs 10 are positioned on their sub-base 26, Fig. 2, and brought one toward the other into their properly aligned positions to have the usual strip 11 therebetween as above indicated, there will be a slight space left between the ends of these opposing tongues 15 and 25.

The tongue 15 is provided with a hole 26 vertically therethrough, and the tongue 25 is similarly provided with a hole 27 vertically therethrough, these holes being located in those portions of the tongues which project beyond their respective inner wall of the well 12 and the edge of the adjacent slab 10. A connector plate 28 is placed over the two tongues 15 and 25 with an intervening fibrous strip 29, preferably treated with some waterproofing compound, such as an asphaltic preparation. Then the bolts 30 and 31 are passed down through holes provided in the plate 28 and the strip 29 thereunder to extend on through the tongue holes 26 and 27. Brought up against the undersides of the tongues 15 and 25 is another strip 32, preferably of fibrous na-

ture and waterproofed, and under this strip 32 is a connecting plate 33 through which the bolts 30 and 31 pass to receive their nuts 34 and 35. Since the tongues 15 and 16 are much less in width than that of the well 12, the nuts may be positioned on the bolts by reaching down alongside and under those tongues. These nuts may then be suitably drawn up to pull the two plates 28 and 33 compressibly toward the tongues 15 and 25 therebetween.

It is to be particularly noted, as indicated in Fig. 2, that the diameters of the bolts 34 and 35 are considerably less than the diameters of the holes 26 and 27 so that there may be permitted longitudinal shifting of one tongue 15 in respect to the other tongue 25 between the connecting plates 28 and 33 without any appreciable vertical shifting, the longitudinal shifting being possibly set up by expansion and contraction of the slabs. The separating strips 29 and 32 are provided to prevent freezing together of the connecting members 28 and 33 with the tongues 15 and 25 so that slippage may be permitted as the occasion demands.

It is further to be noted that where the slabs are to be laid upon a non-level base, one slab may be tilted upwardly or downwardly from the other slab and still be interconnected simply by positioning the connecting plates 28 and 33 as before, and then pulling them down and up respectively against the intervening tongues 15 and 25 (the non-freeze strips being also employed) so that the plates may either bend or the tongues may bend to the angle of inclination between the two slabs, all without eliminating the longitudinally shiftable feature.

The well 12 has the lower portion thereof filled in any suitable manner, such as by a weak mixture of sand and cement 54, the level of this mixture being brought up at least to the undersides of the tongues 15 and 25. Then the upper portion of the well is closed over, first by dropping a rectangular wood block 36 into the well and placing a strip of asphaltated paper 55 therearound to leave an upper groove 37 between the block and the adjacent slab wall wherein a waterproofed compound may be poured to complete the seal. This block 36 is preferably made out of a decay resisting material, such as oak. The underside of the block 36 is notched out as indicated in Fig. 2 to permit that underface of the block to rest upon the connector plate 28. The upper face of the block 36 is at an elevation below the faces of the adjacent slabs 10. The upper edge portion of the slab 10 extending around the well 12 is recessed to leave a shoulder 38 therearound. Then across the edge portion of the next adjacent slab 10 there is also provided a recess 39.

A metal plate 40 is formed to rest within the recesses so provided to have its upper face in the plane of the top faces of the adjacent slabs 10. To secure this plate 40 in place, I pass a pair of bolts 41 and 42 down through the plate 40, through the block 36, to have their lower ends screw-threadedly engage in nuts 53 welded to anchor plates 43 and 44 respectively extending from the opposing side walls of the well 12. These anchor plates 43 and 44 are positioned within the slab 10 at the time it is being formed, and in the present showing consists simply of rectangular members having some sort of a foot packed within the mass of concrete of the slab, the feet in each instance being herein shown simply as a pin 45 extending vertically through the

plate so as to prevent its horizontal shifting from the slab.

In the form herein shown, these bolts 41 and 42 have counter-sunk heads so that they do not project above the top face of the plate 40. The thickness of the wood block 36 may be made to have the plate 40 pulled compressibly thereagainst by the time the plate 40 is pulled down into the recesses 38 and 39 so that the plate is not only supported around its marginal edge portions, but is also centrally supported over the tongues 15 and 25 through the block 36. As above indicated, the slabs 10 are formed with these wells 12 regularly arranged to receive therein the tongues 25 of the adjacent slabs.

While I have herein shown and described my invention in the one particular form, it is obvious that structural variations may be employed, all without departing from the spirit of the invention, and I therefore do not desire to be limited to that precise form beyond the limitations as may be imposed by the following claims.

I claim:

1. A longitudinally yielding, vertically fixed connector of pavement slabs, comprising a pair of tongues each carried by a slab; a base on each tongue rigidly securing it to its respective slab to have the tongue extend therefrom in longitudinal alignment with the other tongue between the top and bottom faces of the slabs; a plate overlapping said tongues; bolts extending through said plate and said tongues to maintain vertical alignment of said tongues, said bolts fitting through said plate and tongues with lost motion to permit limited longitudinal travel of one tongue in respect to the other; and means interposed between said plate and tongues to maintain slidable surfaces therebetween; one of said slabs at least being provided with a well into which the opposing ends of said tongues extend; a well cover seated over said tongues; cover anchor means within said well and fixed to the slab thereof; and means interengaging said cover and said anchor means.

2. A longitudinally yielding, vertically fixed connector of pavement slabs, comprising a pair of tongues each carried by a slab; a base on each tongue rigidly securing it to its respective slab to have the tongue extend therefrom in longitudinal alignment with the other tongue between the top and bottom faces of the slabs; a plate overlapping said tongues; bolts extending through said plate and said tongues to maintain vertical alignment of said tongues, said bolts fitting through said plate and tongues with lost motion to permit limited longitudinal travel of one tongue in respect to the other; and means interposed between said plate and tongues to maintain slidable surfaces therebetween; one of said slabs at least being provided with a well into which the opposing ends of said tongues extend; a well cover seated over said tongues; cover anchor means within said well and fixed to the slab thereof; and means interengaging said cover and said anchor means; said cover being in two parts, one part being an upper pavement face member, and the other part a resilient support member; said support member being carried over said tongues to be supported therefrom.

3. A longitudinally yielding, vertically fixed connector of pavement slabs, comprising a pair of tongues each carried by a slab; a base on each tongue rigidly securing it to its respective slab to have the tongue extend therefrom in longitudinal alignment with the other tongue between

the top and bottom faces of the slabs; a plate overlapping said tongues; bolts extending through said plate and said tongues to maintain vertical alignment of said tongues, said bolts fitting through said plate and tongues with lost motion to permit limited longitudinal travel of one tongue in respect to the other; and means interposed between said plate and tongues to maintain slidable surfaces therebetween; one of said slabs at least being provided with a well into which the opposing ends of said tongues extend; a well cover seated over said tongues; cover anchor means within said well and fixed to the slab thereof; and means interengaging said cover and said anchor means; said anchor means comprising opposing bars extending from opposite faces of said well to have said tongues directed in spaced relation therebetween; and said interengaging means comprising bolts operable from the top side of said cover and screw-threadedly engaging said bars.

4. A longitudinally yielding, vertically fixed connector of pavement slabs, comprising a pair of tongues each carried by a slab; a base on each tongue rigidly securing it to its respective slab to have the tongue extend therefrom in longitudinal alignment with the other tongue between the top and bottom faces of the slabs; a plate overlapping said tongues; bolts extending through said plate and said tongues to maintain vertical alignment of said tongues, said bolts fitting through said plate and tongues with lost motion to permit limited longitudinal travel of one tongue in respect to the other; and means interposed between said plate and tongues to maintain slidable surfaces therebetween; one of said slabs at least being provided with a well into which the opposing ends of said tongues extend; a well cover seated over said tongues; cover anchor means within said well and fixed to the slab thereof; and means interengaging said cover and said anchor means; said anchor means comprising opposing bars extending from opposite faces of said well to have said tongues directed in spaced relation therebetween; and said interengaging means comprising bolts operable from the top side of said cover and screw-threadedly engaging said bars; the underside of said cover being formed to rest on said plate.

5. A pavement comprising a plurality of individual, preformed slabs; tongues fixed to said slabs to extend from edge faces, said tongues being located to be in substantial vertical and longitudinal alignment, one tongue on one slab with an opposing tongue on a next adjacent slab; connector plates overlapping each opposing pair of tongues; bolts clamping together said plates and said tongues to maintain said vertical alignment; said bolts fitting through said plates and tongues to have lost motion sufficient to permit limited relative longitudinal travel between the tongues in each pair thereof; said slabs being formed to have a well therebetween open from the top and into which said pair of tongues extend to permit manipulation of said bolts; a cover for said well; cover anchor means carried within the well; and bolt means interengaging said cover and said anchor means.

6. A pavement comprising a plurality of individual, preformed slabs; tongues fixed to said slabs to extend from edge faces, said tongues

being located to be in substantial vertical and longitudinal alignment, one tongue on one slab with an opposing tongue on a next adjacent slab; connector plates overlapping each opposing pair of tongues; bolts clamping together said plates and said tongues to maintain said vertical alignment; said bolts fitting through said plates and tongues to have lost motion sufficient to permit limited relative longitudinal travel between the tongues in each pair thereof; said slabs being formed to have a well therebetween open from the top and into which said pair of tongues extend to permit manipulation of said bolts; a cover for said well; cover anchor means carried within the well; and bolt means interengaging said cover and said anchor means; a foot on each of said tongues; the vertical opposing faces of said well each being formed to have a tongue foot receiving recess therein; and bolt means operable from within said well for rigidly securing said feet to said faces.

7. A pavement comprising a plurality of individual, preformed slabs; tongues fixed to said slabs to extend from edge faces, said tongues being located to be in substantial vertical and longitudinal alignment, one tongue on one slab with an opposing tongue on a next adjacent slab; connector plates overlapping each opposing pair of tongues; bolts clamping together said plates and said tongues to maintain said vertical alignment; said bolts fitting through said plates and tongues to have lost motion sufficient to permit limited relative longitudinal travel between the tongues in each pair thereof; said slabs being formed to have a well therebetween open from the top and into which said pair of tongues extend to permit manipulation of said bolts; a cover for said well; cover anchor means carried within the well; and bolt means interengaging said cover and said anchor means; said cover being in two parts, one comprising a pavement surface member, and the other a resilient surface member backing shaped to be carried by said tongues.

8. A pavement comprising a plurality of individual, preformed slabs; tongues fixed to said slabs to extend from edge faces, said tongues being located to be in substantial vertical and longitudinal alignment, one tongue on one slab with an opposing tongue on a next adjacent slab; connector plates overlapping each opposing pair of tongues; bolts clamping together said plates and said tongues to maintain said vertical alignment; said bolts fitting through said plates and tongues to have lost motion sufficient to permit limited relative longitudinal travel between the tongues in each pair thereof; said slabs being formed to have a well therebetween open from the top and into which said pair of tongues extend to permit manipulation of said bolts; a cover for said well; cover anchor means carried within the well; and bolt means interengaging said cover and said anchor means; said cover being in two parts, one comprising a pavement surface member, and the other a resilient surface member backing shaped to be carried by said tongues; said bolt means passing through both of said cover parts and being operable by exposed parts at the top side of said cover pavement surface part.

FRANKLIN W. ABEL.
